UNITED STATES PATENT OFFICE.

CHARLES E. LOMBARD, OF EAST WILTON, MAINE.

FIRE-ALARM PISTOL.

SPECIFICATION forming part of Letters Patent No. 718,211, dated January 13, 1903.

Application filed August 18, 1902. Serial No. 120,124. (No model.)

To all whom it may concern:

Be it known that I, CHARLES E. LOMBARD, a citizen of the United States, residing at East Wilton, in the county of Franklin and State of Maine, have invented certain new and useful Improvements in Fire-Alarm Pistols; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to a fire-alarm pistol, and has for an object to provide a pistol which can be used as an ordinary weapon of defense or as an alarm in case of a fire when properly connected with fusible means for operating the trigger thereon upon a dangerous increase in temperature.

Other and further objects and advantages of the invention will be hereinafter set forth, and the novel features thereof defined by the appended claims.

In the drawings, Figure 1 is a side elevation of the invention with parts in section; Fig. 2, a perspective thereof, showing a modified means for controlling the trigger-operating lever; and Fig. 3, a vertical section on line 33 of Fig. 1.

Like letters of reference refer to like parts in the several figures of the drawings.

The letter A designates the barrel of a pistol, which is provided at one end with a handle A', secured thereto by screws A², and at the opposite end with a sight A³. At the handle end of the barrel a breech-clasp A⁴ is pivoted at A⁵ and provided with an aperture A⁶ for the passage of the pin of the hammer A⁷, which is pivoted at A⁸ in the handle. This hammer is formed with a setting-shoulder A⁹ and spring-socket A¹⁰, adapted to receive the end B' of the pivoted trigger B and the end 45 of the firing-spring C, respectively. This spring is held at its opposite end in a socket C' and passes over a bridge C², carried by the handle, so as to be placed under compression when the hammer is raised. The extended end B² of the trigger B is also held under tension by a spring C³, secured at its opposite end C⁴ to the handle, as shown.

D designates a firing-lever which is pivoted to the casing at one end D' and supported at its opposite apertured end D² by an apertured lug D³, carried by the under side of the barrel, over which said end D² passes, and is held by a catch E, having a fusible pin E', passing through the aperture in the lug D³. This catch is pivotally mounted by having its rod 55 E² passed through keepers upon the lever, and the vertical arm E³ of the catch is provided with opposite connecting-eyes E⁴, adapted for use when the pistol is used with an extended fusible wire F, as shown in Fig. 2. 60 The wire thus used is made in sections, which are connected together by a solder fusible at a proper temperature, and at the opposite side of the catch from this wire is a tension-spring F', which acts to throw the catch and 65 permit the lever to operate the trigger when the fusible line is broken by any cause. The firing-lever D is also assisted by a coiled spring D⁶, mounted in a socket D⁶ and bearing upon the upper face of the lever. 70

In the operation of the invention the pistol may be placed in any location or position where a fire is liable to occur, and any dangerous increase in temperature will fuse the pin and cause the lever to strike and operate the trigger, thus exploding the cartridge and sounding an alarm. When the fusible line is used, a much larger area may be protected, as the line may be stretched across an apartment under tension, and when broken 80 by fusing the spring will rotate the catch upon its pivot, thus releasing the lever and firing the pistol to sound the alarm. 85

It will be obvious that changes may be made in the details of construction and configuration of the several parts and in the character of pistols to which the invention is applied, as well as that of the fusible line, without departing from the spirit of the invention as defined by the appended claims. 90

Having described my invention and set forth its merits, what I claim, and desire to secure by Letters Patent, is—

1. In fire-alarm pistol, the combination with a trigger thereof, of a firing-lever pivoted adjacent thereto, a spring for forcing said lever in contact with the trigger a depending lug from the pistol-barrel over which the free end of the lever passes, a pivoted catch mounted

upon said lever and adapted to engage said lug, and means for oscillating said catch, substantially as specified.

2. In a fire-alarm pistol, the combination with a trigger thereof, of a firing-lever pivoted adjacent thereto, a spring for forcing said lever in contact with the trigger a depending lug from the pistol-barrel over which the free end of the lever passes, a pivoted catch mounted upon said lever, and adapted to engage said lug, a fusible line connected to one side of said catch, and a tension-spring connected to the opposite side thereof, to oscillate the catch when the line is broken, substantially as specified.

3. In a fire-alarm pistol, the combination with the barrel thereof, of a breech-clasp pivotedly mounted thereon, and provided with a firing-aperture, a hammer mounted to coöperate with said aperture, and a trigger

for releasing said hammer, an angular lever pivotally mounted in advance of said trigger, and provided upon its under face with bearing-lugs, a catch pivotally mounted in said lugs, to operate at a right angle to said lever, a spring for holding the lever under tension, a depending lug from the pistol, adapted to pass through said lever, and provided with an aperture to receive the end of said catch, and connecting-eyes disposed upon the opposite sides of said catch for the purpose of oscillating the same, substantially as specified.

In testimony whereof I hereunto affix my signature in presence of two witnesses.

CHARLES E. LOMBARD.
